LADY'S STOCKING

Charlie A. Miles, Burlington, N. C.

Application May 14, 1951, Serial No. 15,167

Term of patent 14 years

(Cl. D47—7)

To all whom it may concern:

Be it known that I, Charlie A. Miles, a citizen of the United States of America, residing at Burlington, in the county of Alamance, State of North Carolina, have invented a new, original, and ornamental Design for a Lady's Stocking, of which the following is a specification, reference being had to the accompanying drawings, forming a part thereof.

Figure 1 is a side elevation of the complete lady's stocking showing my new design;

Figure 2 is a fragmentary rear elevation of the stocking looking at the left-hand side of Figure 1.

The stocking is characterized by having the rearmost portion of the heel pocket and high splice and the longitudinal center of the sole of a yarn contrasting to the yarn of the body of the stocking and having the forward portions of the high splice and heel pocket and each of the side portions of the sole of a yarn contrast-

ing to the yarn of both the body of the stocking and the rearmost portions of the high splice and heel pocket, the width of the forward portions of the high splice and forward portions of the heel pocket increasing in width from top to bottom in a series of steps.

I claim:

The ornamental design for a lady's stocking, substantially as shown and described.

CHARLIE A. MILES.
